DRAWING ROLL

Jan Weinberger, Lowell, Mass.

Application July 30, 1938, Serial No. 222,282

2 Claims. (Cl. 19—130)

This invention relates to a drawing roll and has relation more particularly to a top drawing roll, and it is primarily an object of the invention to provide a top roll so constructed and assembled 5 to act upon the sliver passing therebelow to effectively control the short fibres that may be in the sliver which are not controlled by the entry or delivery rolls and thereby substantially eliminating the liability of bunches forming in the sliver. 10 It is also an object of the invention to provide a top drawing roll including a part for direct contact with a sliver, said part being so constructed and arranged as to have three different movements, namely, rotatable, axial and radial. 15 The invention consists in the details of construction and in the combination and arrangement of the several parts of my improved drawing roll whereby certain important advantages are attained and the device rendered simpler, less 20 expensive and otherwise more convenient and advantageous for use, as will be hereinafter more fully set forth.

The novel features of my invention will herein-after be definitely claimed.

In order that my invention may be the better understood, I will now proceed to describe the same with reference to the accompanying drawing, wherein:

Figure 1 is a diagrammatic view in section illustrating the roll arrangement as herein embodied;

Figure 2 is a view partly in section and partly in elevation illustrating a pair of coacting draft rolls constructed in accordance with an embodiment of my invention;

Figure 3 is a longitudinal sectional view with parts in elevation taken through the upper roll structure, the roll having been revolved through 180° from that shown in Fig. 2.

Figure 4 is a fragmentary end elevational view illustrating the general type of bearing employed in connection with the roll assembly as herein disclosed.

My improved roll as herein disclosed is to be substituted for a top roll of a conventional drawing machine, roving frame or kindred structures used in the textile industry.

In the present embodiment of my invention I disclose a drawing machine of a type including the bottom rolls 1, 2, 3 and 4, the roll 1 constituting the delivery roll, the roll 2 constituting the entry roll, and the rolls 3 and 4 constituting intermediate draft rolls.

Coacting, as is well known, with the delivery roll 1 is a top delivery roll 5 and coacting with the entry roll 2 is a top entry roll 6. Coacting with

each of the draft rolls 3 and 4 is a top draft roll constructed in accordance with my invention. While I disclose one of my improved top rolls used in connection with each of the intermediate or draft rolls, it is to be understood that oftentimes it is only necessary that one of my improved rolls be used. As is now well known, the rolls 1, 2, 3 and 4 successively have increased peripheral speed. However, as this forms no part of my present invention a detailed description and illustration 10 is believed to be unnecessary. The rolls 5 and 6 are weighted in a conventional manner.

My improved roll as herein disclosed comprises an elongated arbor or shaft 7, the extremities of which are rotatably received within the bearing blocks 8. Each of these bearing blocks 8, as herein disclosed, is freely mounted in a vertically disposed slot 9 whereby the bearing block is free for up and down movement. These bearing blocks 8 have flattened faces 10 for direct contact 20 with the side walls of the slots 9 so that the bearing blocks 8 will be held against rotation.

The arbor or shaft 7 has its central portion 11 of increased diameter whereby are provided longitudinally spaced surrounding shoulders 12 with 25 which contact the internal shoulders 14 of the collars 15 which freely surround the arbor or shaft 7 and the adjacent end extremities of the enlarged portion 11. The outer ends of these collars 15 are square while the inner ends 16 are 30 disposed on a predetermined bevel, preferably six degrees although, of course, I do not wish to be understood as limiting myself to this exact degree.

Interposed between the collars 15 are the tubular members or sections 18 of required lengths 35 and of any desired number. These members or sections 18 are tubular and the interior diameter of each of these tubes or sections 18 is materially greater than the diameter of the portion 11 of the arbor or shaft 7. The ends 19 of these members or sections 18 are also disposed on a predetermined angle, preferably six degrees, whereby the ends of the sections or members 18 may be termed as cam ends for coaction with each other and with the ends 16 of the collars 15 to cause the 40 members or sections 18 to have back and forth axial movement during the rotation of a member or section 18 to fluff the sliver as it passes between such section or member 18 and the coacting bottom draft roll 3 or 4. The extremities of the 50 arbor or shaft 7, as hereinbefore stated, are rotatably received within the bearing blocks 8 in order to assure a minimum of friction between the sleeves 18 and the arbor or shaft 7 as any tendency to undue friction between the sleeves 55

18 and the arbor or shaft 7 will result in rotation of said arbor or shaft.

5 The collars 15 are of a diameter in excess of the diameters of the members or sections 18 and such relative diameters are such that at no time does any portion of a member or section 18 extend beyond the periphery of the collar 15.

10 The collars 15 on the shaft or arbor 7 have frictional contact from above with the collars 20 fixed to the end portions of a draft roll 3 or 4 whereby the shaft or arbor 7 is normally spaced a predetermined distance from the associated roll 3 or 4 with the shaft or arbor 7 in parallelism with such roll 3 or 4.

15 The speed of a sliver as drawn increases as it passes over the bottom rolls of increasing speed whereby the desired stretching of the fibres is obtained which is in accordance with the well known practice. A sliver, as is well known, comprises fibres of varying lengths and with the use of a roll or rolls constructed in accordance with an embodiment of my invention the short fibres, which would otherwise float without control between the entry and delivery rolls, are prevented 20 from bunching as the action of my improved roll or rolls results in a fluffing of the sliver and thus avoids the short fibres having adhesion to the longer fibres.

25 By having the separate members or sections 30 18, it is believed to be clearly apparent that each of said sections or members 18 is free to rotate independently of the other as the sliver is drawn therebeneath and as the interior diameter of each of the members or sections 18 35 is greater than the diameter of the adjacent portion of the shaft or arbor 7, said member or section 18 will also have free movement in substantially a radial direction or upwardly in order to compensate for varying thicknesses of the sliver 40 or an increased thickness which may be caused by a bunching. This radial and rotary movement of a member or section 18 is insufficient to properly fluff the sliver, or more particularly a bunch in the sliver, but effective fluffing is assured 45 by the reciprocal axial movement of the member or section 18 which readily occurs irrespective of the rotary or radial movement hereinbefore referred to.

50 As is well known, as a sliver travels through the drawing rolls it has a tendency to have side movement or, in other words, does not at all times move forwardly in a fixed path of travel. If the ends of the sections or members 18 were square the side movement of the sliver on one 55 section or member 18 would at times strike the end of an adjacent member or section 18 with undesirable results. However, by having the ends of the members or sections 18 beveled, as hereinbefore stated, should the side movement of a 60 sliver on one member or section 18 have a tendency to pass beyond the end of such member or section 18, the adjacent end portion of the succeeding member or section 18 will readily ride thereover.

65 A more important feature, however, of these beveled ends of the members or sections 18 is to effect a reciprocal endwise movement of said members or sections 18 in an axial direction. This reciprocal endwise movement of the members or sections 18 is assured due to the difference of speed between the collars 15 and the sections or members 18. The collars 15 travel at a fixed speed as determined by the speed of the collars 20 on a bottom roll 3 or 4. The diameters of the collars 20 on the bottom roll 75

5 8 or 4 are less than the diameter of the central working portion of the bottom roll 3 or 4 whereby the peripheral speed of such collars 20 is less than the peripheral speed of the working portion of the roll 3 or 4.

10 Each of the slivers passing under a member or section 18 travels at a speed higher than the peripheral speed of its associated bottom roll 3 or 4, such speed of the sliver being influenced by the delivery rolls.

15 As before stated, the peripheral speed of the roll 3 or 4 is greater than the collars 20 thereon. This is of importance because it is a result of this difference in speed that the reciprocal axial movement of the members or sections 18 20 is effected. It is also believed to be obvious, in view of the foregoing, that each of the members or sections 18 is capable of a peripheral speed greater than that of the others. This difference in peripheral speeds is of advantage 25 as under certain conditions a member or section 18 may have contact with both the roll 3 or 4 and a sliver and under which conditions the rotation of the member or section would be approximately one-half the difference in relative 30 speeds of the working periphery of the roll 3 or 4 and the sliver. It is believed, therefore, to be obvious that in the effective action of the members or sections 18 three separate speeds are indicated as a, b and c in Figure 2 of the drawing. The peripheral speed a of the collars 15 is less than the peripheral speed b of the working portion of a roll 3 or 4 while the speed c of the sliver S is greater. These variations in speed 35 together with the beveled ends of the sections or members 18 and the beveled ends of the collars 15 assure the desired reciprocating axial movement of the members or sections 18.

40 In connection with my improved roll no cleaner is required to prevent the fibre from wrapping therearound as such wrapping is entirely avoided by the axial reciprocation of the members or sections 18 as hereinbefore mentioned.

45 From the foregoing description it is thought to be obvious that a drawing roll constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

55 I claim:

1. In a drawing apparatus of the class described, a bottom roll, a shaft supported above the bottom roll, collars on the shaft, means for rotating said collars at a peripheral speed slower than the peripheral speed of the working portion of the bottom roll, the opposed faces of the collars being beveled, separate tubular members 60 surrounding the shaft and disposed along the space between the collars, the ends of said tubular members being beveled, adjacent extremities of the members contacting with each other and the outer extremities of the end tubular members having contact with the beveled faces of the collars on the shaft, the interior diameters of the tubular members being greater than the diameter of the associated portion of the shaft, and means for drawing a sliver between the 65 70 75 80 85 90 95 98 99 100

lower roll and one of the tubular members at a speed higher than the peripheral speed of the working portion of the lower roll.

5 2. In a drawing apparatus of the class described, a bottom roll, a shaft rotatably supported above the bottom roll, collars rotatably mounted on the shaft and having driven engagement with the bottom roll, the opposed faces of the collars being beveled, separate tubular members surrounding the shaft and disposed along the space between the collars, the ends of

said tubular members being beveled, adjacent extremities of the members contacting with each other and the outer extremities of the end tubular members having contact with the beveled faces of the collars on the shaft, the interior 5 diameters of the tubular members being greater than the diameter of the associated portion of the shaft, and means for drawing a sliver between the bottom roll and one of the tubular members.

10 JAN WEINBERGER.
